UNITED STATES PATENT OFFICE.

CHARLES J. BAYER, OF POUGHKEEPSIE, NEW YORK.

IMPROVED RAILWAY-SWITCH.

Specification forming part of Letters Patent No. **57,661**, dated September 4, 1866.

To all whom it may concern:

Be it known that I, CHARLES A. BAYER, of Poughkeepsie, Dutchess county, State of New York, have invented a new and Improved Railroad-Switch; and I do hereby declare that the following is a full, clear, and exact description thereof, which will enable others skilled in the art to make and use the same, reference being had to the accompanying drawings, forming part of this specification, in which—

Figure 1 is a plan or top view of my invention; Fig. 2, a transverse section of the same, taken in the line *x x*, Fig. 1.

Similar letters of reference indicate like parts.

This invention relates to a new and improved railroad-switch of that class which are designed to be, in a measure, self-acting, or which may be operated by the car-wheels, so as to be brought in proper position when the cars are moving in one direction, the switch requiring to be adjusted by hand when the cars are moving in the opposite direction.

The object of the invention is to prevent accidents by a careless management of the switch, by having the latter adjusted with certainty by the car-wheels when the cars are moving in a direction in which accidents would invariably occur if the switch be in a wrong position.

A A represent the rails of a main track, and B B' the rails of a branch track. C C represent the switch-rails, one end of which work on pivots or pins, as usual, and their opposite or disengaged ends are connected to bars D D', which are attached to the rails A' B' of the main and branch tracks by joints *a*, or any flexible attachment, and the opposite ends of said bars are connected to the switch-rails in a similar manner, as shown at *b*.

The bars D D' may be rigid or be flexible, so as to have a spring-like action.

The switch-rails C C are connected by a cross-rod, *c*, one end of which projects beyond the switch, and is connected, as usual, to a hand-lever, E, by which the switch may be adjusted whenever necessary.

By referring to Fig. 1 it will be seen that the bars D D' are by the sides of the rails A' B' of the main and branch tracks, and the inner sides of these rails directly opposite the bars D D' are beveled or inclined, as shown

at *d*, Fig. 2, to correspond to the sides of the bars D D', which are similarly beveled, as shown at *e*. These beveled or inclined surfaces form a lock, and prevent the bars D D' from rising.

When the switch-rails C C are in line with the rails A A' of the main track, as shown in black in Fig. 1, the cars can pass over the main track in either direction; and in case a car is passing from the branch rails upon the main rails in the direction indicated by arrow 1, the flanges of the wheels at the left-hand side of the car will press the bar D laterally in the direction indicated by arrow 2, and the switch-rails will be moved in line with the branch rails B B, as shown in red, Fig. 1. In case a car, afterward, moves along on the main rails A A' in the direction indicated by arrow 3, the flanges of the right-hand wheels will press the bar D laterally in the direction indicated by arrow 4, and move the switch-rails C C back in line with the rails A A of the main track. Thus it will be seen that the car-wheels adjust the switch when the cars are moving in the direction indicated by arrows 1 and 3, and no accident can occur when the cars are moving in this direction on either track, for if the switch-rails are not adjusted in lines with the rails on which the cars are traveling the car-wheels will adjust the switch in line with said rails.

When a car is moving in an opposite direction on the main rails, as indicated by the arrow 5, the switch requires to be adjusted by hand; but in this case no accident can occur if the switch be in a wrong position, as the car will simply pass on the wrong track, and it can be backed on the main rails, the switch adjusted, and the car then again move forward, occasioning only a trifling delay.

I am aware that Letters Patent were granted July 24, 1860, for an improved switch-plate for street-railways, which switch-plate is undercut or recessed to receive a vertically-dovetailed tongue.

Having thus described my invention, I claim as new and desire to secure by Letters Patent—

1. The connecting of the switch-rails C C to the main and branch rails A' B' by means of the bars D D, substantially as shown, so that

the switch-rails will be adjusted or moved by the action of the car-wheels on the bars D D, as described.

2. In a railway-switch adapted to operate substantially as herein described, having the adjoining sides of the rails A' B' and the bars D D beveled or inclined to form a lock for the bars D D, as set forth.

The above specification of my invention signed by me this 29th day of January, 1866.

CHAS. J. BAYER.
